(57) **CLAIM**

The ornamental design for an LED lamp, as shown and described.

DESCRIPTION

FIG. 1 is a perspective view of an LED lamp showing my new design.

FIG. 2 is a front elevational view thereof.

FIG. 3 is a rear elevational view thereof.

FIG. 4 is a left-side, elevational view thereof.

FIG. 5 is a right-side, elevational view thereof.

FIG. 6 is a top plan view thereof.

FIG. 7 is a bottom plan view thereof.

FIG. 8 is a view similar to FIG. 4, showing a mounting sleeve of the LED lamp being swiveled to an inclined orientation; and,

FIG. 9 is a view similar to FIG. 4, showing the mounting sleeve of the LED lamp being swiveled to another inclined orientation.
